UNITED STATES PATENT OFFICE.

GEORG SPIESS, OF LEIPZIG-REUDNITZ, GERMANY.

PAPER-SHEET-FEEDING MACHINE.

1,091,444.

Specification of Letters Patent. Patented Mar. 24, 1914.

Application filed December 20, 1913. Serial No. 808,020.

To all whom it may concern:

Be it known that I, GEORG SPIESS, residing in Leipzig-Reudnitz, Germany, have invented certain new and useful Improvements in 5 Paper-Sheet-Feeding Machines, of which the following is a specification.

In paper sheet feeding mechanism in which the uppermost sheet of the pile is advanced by combing wheels, the combing 10 wheel which has advanced the sheet to a determined point must be at once raised from the working surface in order to enable the sheet to be correctly adjusted prior to its continued delivery. This adjustment is 15 initiated by a feeler which is raised by contact with the edge of the advancing sheet. The raising of the combing wheel is then effected under the action of a powerful 20 spring, that is to say, abruptly, and since the individual parts of the mechanism are not all in direct connection with one another, their connection must be reestablished during each rotation. Owing to these 25 defects it was hitherto impossible to increase the speed of the sheet adjusting mechanism beyond 60 per minute.

Now according to this invention the lever arm from which the feeler is flexibly suspended is to be locked by one member of a 30 toggle lever. That member carries a roller, adapted to bear on a corresponding face of the feeler carrier so that the whole movement of throwing the combing wheel in and out of action is effected under the influence 35 of a closed lever mechanism of which all individual levers which are not directly connected one to another are forcibly held in contact under the action of a spring or the like.

40 The accompanying drawing illustrates a preferable construction of this invention.

Figure 1 is an elevation of the sheet feeding mechanism in the operative position of the combing wheels. Fig. 2 shows the same 45 view with the parts in the position in which the combing wheel has been raised from the working surface. Fig. 3 is an illustration of the parts viewed from right to left in Fig. 2, and Figs. 4 to 6 represent the 50 releasing means in three different positions on a somewhat enlarged scale.

The mechanism is adapted to transfer in a known manner by means of combing wheels A individual sheets from a pile of 55 sheets supplied by means of a known supply roller, to transfer rollers. The comb-

ing wheels A are constantly rotated by a toothed gearing likewise in a known manner and to be raised or lowered by means of an arm C engaging with the end of a lever B. 60 Now in order to render the combing wheel A inoperative, that is to say, in order to actuate the levers B, C and D, according to this invention, a toggle lever E, F, is used which is arranged under the action of a 65 spring G. Normally, as shown in Fig. 1, this spring is in tension or cocked. The feeler I is in a known manner flexibly suspended from a lever arm H and the latter in the present instance is adapted to lock the 70 toggle lever E, F, when its toggles are in stretched condition. As shown, the lever H is provided with a spring-actuated pin or like member K which is adapted when the parts are in their normal position (see 75 Fig. 4) to engage with the edge of a lug L forming an offset extension of the toggle F. These locking members are held in contact with one another by means of a traction spring L', of which one end is attached to 80 the lug L and the other to a lug N on the lever H, and this spring has the function to hold the lugs L and N in contact with one another at all times during the raising or lowering of the combing wheels. To this 85 end the lug L carries a roller M and the lug N is provided with an oblique face so that the roller M is in contact with this oblique face, as shown in Fig. 6, even after the engagement between the locking parts 90 K and L has been released. This yielding connection of the two locking parts is of course without any effect upon the movement of the feeler I which as shown is freely connected to the arm H. When the feeler I 95 is tripped up by the edge of a sheet advanced by the combing wheel A, its free end is in a known manner brought into engagement with a toothed disk O mounted on a constantly rotating shaft P and by this engagement the lever H is rocked so as to release the locking members K and L and accordingly the toggle lever E and F to the action of the spring G which tends to stretch the toggles and thereby to raise the combing wheel. In this action the roller M moves along the inclined face on the lug N until the position indicated in Figs. 2 and 6 is attained. 100

The resetting of the parts and the cocking of the spring G is effected according to this invention from a shaft Q by means of 110

a cam R. By preference, the cam R may be mounted on the same shaft carrying the cam disk S which is adapted to actuate the lever T arranged to adjust the upper transfer roller U. The arrangement according to this invention has the advantage of enabling a yielding mechanical connection between the toggle lever and the feeler carrier to be permanently maintained and therefore 10 the raising and lowering movement of the combing wheels to be effected without any shocks and consequently the speed of the sheet feeder to be raised if desired to 150 revolutions per minute.

15 What I claim and desire to secure by Letters Patent is:

1. A paper sheet feeding device comprising in combination a combing roller, means associated therewith for raising same, a 20 lever arm, a flexible feeler suspended therefrom, a toggle lever having one end in operative contact with said raising means and the other adapted to bear against said lever arm, a spring exerting tension on said toggle lever, and locking means carried on said lever arm for holding the toggles of said toggle lever normally extended and the combing roller in its lowered position.

2. A paper sheet feeding device comprising in combination a combing roller, a carrier member having a flexible feeler mounted thereon, levers adapted to raise said combing roller, a toggle lever having its lever ends in contact with said carrier and 35 said first mentioned levers respectively, a traction spring tending to hold said toggles contracted, and locking means on said carrier for maintaining said toggles in their extended position and the combing wheel in 40 its lower position.

3. The combination with a paper sheet feeding device having a combing roller and a flexible feeler, of means initiated by said feeler for raising and lowering said combing roller comprising a carrier for said 45 flexible feeler, lever arms associated with said combing wheel, a toggle lever coacting with said lever arms and said carrier, a spring connected to said toggle lever and tending to hold said toggles in their contracted position, locking means mounted on 50 said carrier and adapted to normally hold said toggle lever in its extended position against the tension of the traction spring.

4. A paper sheet feeding device comprising in combination, a combing roller, means associated therewith for raising same, a lever arm, a flexible feeler suspended therefrom, a toggle lever having one end in operative contact with said raising means and 60 the other adapted to bear against said lever arm, a spring exerting tension on said toggle lever, locking means carried on said lever arm for holding the toggles of said toggle lever normally extended and the 65 combing roller in its lowered position, said locking means adapted to be released by the action of the flexible feeler, whereupon said toggles are contracted and said combing roller is raised, and means coacting with 70 said lever arm adapted to restore the toggles to their normal position and reset the locking means and combing roller, respectively.

In testimony whereof I have affixed my signature in presence of two witnesses.

GEORG SPIESS.
